UNITED STATES PATENT OFFICE.

NICHOLAS CARPENTER, OF ELLENVILLE, ASSIGNOR TO HIMSELF, S. B. SMITH, E. J. GENNET, AND H. KELLER, OF NEW YORK, N. Y.

IMPROVED MACHINE FOR CLEANING AND SEPARATING ORES.

Specification forming part of Letters Patent No. 42,558, dated May 3, 1864.

To all whom it may concern:

Be it known that I, NICHOLAS CARPENTER, of Ellenville, of the county of Ulster, in the State of New York, have invented certain new and useful Improvements in Machinery for Jigging Lead and Other Ores; and I do hereby declare that the following is a full and exact description thereof, reference being had to the accompanying drawings, making part of this specification.

My invention relates to that portion of the machinery employed in separating and cleaning ores known as "jigging" machinery, and has for its objects to overcome certain practical difficulties, which have heretofore rendered such machinery comparatively valueless, and to render such machinery capable of successful operation and of producing a much larger percentage than heretofore of pure metal from a given mixture of metal and foreign matter.

Previous to my invention jigging-machines have been made in which the "hutch" was rectangular in form; but practice has shown that with a hutch thus shaped the action of the water on the "save-alls" is such as to render it necessary for the operators to keep constantly turning the latter in their seats, in consequence of the contents thereof being acted on more violently on one side (that nearest the "bob") than on the other, and experience has shown that a considerably larger percentage of pure metal should be derived than can be gotten out by this kind of hutch. To avoid the necessity of turning the save-alls, and to produce a hutch in which a larger percentage of pure metal can be derived, and from which the pure metal collected can be more easily removed with less hand-labor, are the objects of the first part of my invention, which consists in making the hutch in the form of an inverted frustum of a square pyramid, whereby the action of the water, when moved by the bob or plunger, is such as to operate equally on every portion of the save-alls, and the pure metal accumulated will be induced to discharge itself when the doors of the hutch are opened.

Previous to my invention it has been customary to arrange a stuffing-box in the top of the hutch through which the bob or plunger shaft or rod worked about air-tight; and in a

machine thus constructed it was with difficulty that the operators could remove the save-alls, it being necessary also to lift the save all during the downward stroke of the plunger, as during the upward stroke the tendency of the atmosphere to rush down through the save-alls to fill the vacuum created by the removal of the plunger creates such a pressure on them as to prevent their being lifted from their seats. I have discovered that the plunger and its rod may work loosely through the top of the hutch, so as to admit of a free ingress and egress of the air, and the above-named objection be thereby effectually overcome without any material escape of water from the hutch around the plunger; and the second part of my invention consists in so constructing the plunger and hutch-top and arranging them together as that there will be an annular opening surrounding the plunger in the hutch-top of sufficient capacity to admit of the free ingress and egress of the air during the strokes of the plunger, substantially as and for the purpose more fully set forth hereinafter.

Previous to my invention it has been customary to convey the crushed rock and ore, mixed, from the crusher to the screen, and thence to the hopper, from which the save-alls are supplied by hand-labor. The third part of my invention consists in the arrangement with the hopper of a conveyer or elevator so constructed and arranged relatively with the screen and hopper as to receive the crushed material from the screening-machine and convey it to and discharge it into the hopper, as will be hereinafter more fully explained.

To enable those skilled in the art to make and use my invention, I will proceed to describe the construction and operation of my improved jigging machinery, referring by letters to the accompanying drawings, forming part of this specification, and in which—

Figure 1 is a top or plan view of one of my improved jigging-machines. Fig. 2 is a vertical section of the same at the line A A, Fig. 1. Fig. 3 is a partial vertical section at the line B B, Fig. 1; and Fig. 4 is a detail view, in cross-section (at y y, Fig. 1) and plan, increased scale, of the save-all.

In the several figures the same parts are indicated by the same letters of reference.

In Fig. 2 the save-alls are drawn in section and the driving-pulley in elevation, to illustrate more clearly, though the former, it will be understood, are beyond, and the latter in front, of the plane of section.

A is the main frame-work, on the top of which are arranged, running parallel with each other, three cross-beams, B B' B², which serve to sustain the pillow-blocks of the two pulley-shafts g g', and also the block P. On this latter is secured a cast-iron stand, m, in which rests and turns (in suitable bearings) the fulcrum pivot l of the vibrating arm or beam h, at one end of which is arranged the shoe or strap s, which is pivoted at r to the upper end of the pitman i; and near the other end of arm h is secured the shoe or strap x, which is pivoted at p (see Fig. 3) to the upper end of a pitman, (not shown,) the lower end of which is connected to the crank-pin of a face-plate, n, (see Fig. 1,) which is fast on the end of shaft g. The lower end of pitman i is connected to the upper end of the rod or vertical shaft J, on the lower end of which is arranged the bob or plunger K.

On the two shafts g g' are secured two cone-pulleys, L and M, which are belted together in the usual way, and on shaft g' are also keyed a fast and loose pulley, N O, on which runs the main driving-belt of the machine.

I is the hopper, into which the crushed rock and ore are conveyed from the screen by means of the elevator R, which may be made in the usual manner, and driven by a belt from the pulley L, or in any other desirable manner. The hopper I is made with a vertical hollow shaft, through which works vertically the bob-shaft J. (See Figs. 2 and 3.)

E is the hutch, which is constructed of suitable boards bolted to corner timbers, and the whole properly strengthened by side braces or timbers, F, and cross ties G, on which latter the hopper I may be supported. This hopper, as also the hutch E, is provided with a door on each side, near the bottom, as seen at a and a², the doors in hopper I being for the purpose of allowing a supply to the save-alls in the usual manner, and the doors in hutch E being used to allow the escape of the contents of the hutch after the jiggling operation is finished. The hutch E is covered over by a cover, d, arranged in the usual manner, about even with the floor C, and in which cover d are four circular openings, into which fit four tapering thimbles, e, which are made of cast-iron, with a flange projecting outward from their top edge so as to rest on the cover d, and an annular inner flange at their lower edge, on which rests the save-all f, which is made in the usual manner, with a sieve or wire gauze for its bottom. The cover d is made with an annular or cylindrical flange or projection, c, within which works up and down the plunger K. This plunger K should be made somewhat less in diameter than the internal diameter of the cylindrical

flange c, so as to leave an annular space between the said flange and plunger sufficient for the escape and return of the air during the strokes of the plunger—say one-eighth of an inch on a full-size machine. The position of the four save-alls is clearly seen at Fig. 1, and the detail construction of each will be clearly understood from Figs. 1 and 4. The hutch E should be properly supported on timbers H over the floor D, in the usual manner.

I have not shown the screening machinery in the drawings, as my invention does not relate to any portion or peculiarity of such machine, and it will be understood to be so located as to discharge the screened material into the buckets of the elevator or conveyer R.

The operation of my improved jiggling machinery may be thus briefly explained: The hutch E being properly supplied with water in the usual manner, and the hopper I kept supplied with material from the screen by the conveyer R, power is applied to the shaft g', and thence through the medium of a band passing over pulleys L and M to the shaft g, which, by means of the crank and pitman, as before explained, imparts the requisite motion to the vibrating arm or walking-beam h in the ordinary manner, and through the pitman I effects the reciprocating motion in the vertical shaft J, which carries the plunger K, which bobs in the water in the hutch and causes the washing-out of the save-alls of the foreign substances and the separation of the fine metal on the principle familiar to those skilled in the art. The save-alls f are filled by the operators from the hopper I by opening one or another of the doors a², and when a sufficient quantity of ore has been jigged the fine metal in the hutch is secured by simply opening the doors a. The save-alls are kept charged at their bottoms with a sufficient layer of pure metal in the usual manner, and the rock and surplus metal kept out constantly by the operators in the manner well known.

It will be understood that in the old rectangular form of hutch the water acted much more violently on that portion of the save all which was nearest to the plunger, so that the operators had to keep constantly turning round the save-all and presenting the different portions thereof toward the plunger to effect an equal jiggling of all the material in the save-all, whereas in my improved form of hutch the water acts evenly and uniformly on all portions of the save-all, and jigs its contents evenly, while the save-all remains stationary.

It will also be understood that in consequence of the tapering form of the hutch E the fine metal which descends therein is washed much cleaner, and the deposit in the hutch has a much larger percentage of pure metal than has ever yet been derived by the jiggling operation, and also that by having the hutch E tapering toward the bottom, as shown, it will almost or quite empty itself when the doors a are opened, thus dispensing with a

a great deal of hand-labor required in cleaning the fine metal and slime out of the old-fashioned rectangular hutch.

By affording a sufficient opening around the plunger K for the entrance and escape of air during the strokes of the bob or plunger K the save-alls are relieved of all pressure tending to retain them in their seats, and may be readily lifted by the operators at any and all times for cleaning out and recharging in the usual manner.

The large amount of hand-labor heretofore expended in carrying the material from the screen to the hopper I, it will be seen, is dispensed with by the arrangement of a conveyer connecting the screen with the hopper.

The object and advantage of the cone-pulleys are to change the speed of the jiggling machinery relatively to that of the main driver, in order that the plunger may be maintained at the given requisite speed, while the speed of the main driver or motor may, from various causes, vary very materially.

The working of my improved jiggling machinery has demonstrated a practical gain of about twenty-five per cent. in the percentage

of pure metal derived by the jiggling operation.

Having fully described the construction and operation of the several features of my invention, so that any one skilled in the art can make and use the same, what I claim as new, and desire to secure by Letters Patent, is—

1. A hutch which is made tapering from the top toward the bottom, substantially as and for the purposes set forth.
2. So constructing and combining the plunger and hutch as to admit of the ingress and egress of the air around the plunger, or in any other manner, as and for the purpose described.
3. The combined arrangement of an elevator or conveyer, R, with the hopper I, and any suitable screen, as and for the purpose hereinbefore set forth.

In testimony whereof I have hereunto set my hand and seal this 29th day of January, 1864.

NICHOLAS CARPENTER. [L. S.]
In presence of—

PETER VAN BUREN,
ANDREW J. VAN DUGEE.
